CLAIM

The ornamental design for a garment with pockets, as shown and described.

DESCRIPTION

FIG. 1 is a perspective view of a garment with pockets showing my new design;

FIG. 2 is another perspective view thereof;

FIG. 3 is a front view thereof;

FIG. 4 is a rear view thereof;

FIG. 5 is a side view thereof;

FIG. 6 is an opposite side view thereof;

FIG. 7 is a perspective view of a garment with pockets showing another embodiment of my new design;

FIG. 8 is another perspective view thereof;

FIG. 9 is a front view thereof;

FIG. 10 is a rear view thereof;

FIG. 11 is a side view thereof;

FIG. 12 is an opposite side view thereof;

FIG. 13 is a perspective view of a garment with pockets showing another embodiment of my new design;

FIG. 14 is another perspective view thereof;

FIG. 15 is a front view thereof;

FIG. 16 is a rear view thereof;

FIG. 17 is a side view thereof; and,

FIG. 18 is an opposite side view thereof.

The broken lines depict portions of the garment that form no part of the claimed design.

1 Claim, 15 Drawing Sheets
